(57) **CLAIM**

The ornamental design for a vehicle, toy, and/or replica, as shown and described.

DESCRIPTION

FIG. 1 is a left-side, top, perspective view of a vehicle, toy, and/or replica showing our new design;

FIG. 2 is a front perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left-side elevational view thereof, the right-side elevational view is a mirror image of the left-side; and,

FIG. 8 is a right-side bottom perspective view thereof. The broken lines depict portions of the vehicle, toy, and/or replica that form no part of the claimed design.
